UNITED STATES PATENT OFFICE.

ARTHUR K. TAYLOR, OF BALTIMORE, MARYLAND, ASSIGNOR TO TAYLOR REGISTER-
ING PROJECTOR COMPANY, OF BALTIMORE, MARYLAND.

PLATE MOUNTING.

Application filed February 6, 1923. Serial No. 617,339.

To all whom it may concern:

Be it known that I, ARTHUR K. TAYLOR, a citizen of the United States, and a resident of Baltimore, Maryland, have invented 5 a new and useful Plate Mounting, of which the following is a specification.

My invention relates to improvements in plate mountings for printing plates, such as electrotype plates. The objects of my invention are: first, to secure a light mounting which can be made in large size and yet be readily handled; second, to secure a mounting which will not warp and which will be influenced by moisture and temperature to a minimum degree; third, to secure a mounting to which plates may be readily attached and on which they can be attached in any position; fourth, to secure a mounting that can be made the correct thickness 15 all over, even to $1/1000$ of an inch; fifth, to secure a mounting that can be easily repaired; and sixth, to secure a mounting that will not be distorted because of unequal pressure when it is clamped to the bed of 20 the press.

I attain these objects and other apparent advantages by the device illustrated in the accompanying drawings in which Fig. 1 is a plan view of the plate mounting; Fig. 2 25 is a front elevation with the front part of the rim 6 removed. Fig. 3 is a partial cross-section on line 3—3 of Fig. 1, looking in the direction of the arrows. Fig. 4 is a perspective of one of the wooden blocks.

Similar numerals refer to similar parts throughout the several views.

The base 1 is made up of aluminum, steel or any other rigid, tenacious material. Square blocks of wood 2 are placed on the 30 base, and attached to it preferably by screws 3, the heads of which are countersunk in the base as shown in Fig. 3. These wooden blocks may be made of several layers of wood, the grain of each layer running in a 35 direction different from that of the other layers as shown in Fig. 3, so that the blocks will not warp in any direction. Fig. 4 shows a perspective view of one of the blocks. These blocks are not placed in contact with each other under normal atmospheric conditions, thus allowing for swelling 40 without buckling and also allowing for ready replacement. The blocks are arranged so that their edges are oblique to the 45 edges of the base. Near the edges of the

base, pieces of blocks 4 are put in to fill up the whole surface. Around these blocks and fastened preferably by screws 5 to the top of the base, is a metal rim 6 which makes a rigid member to fasten the clamps 60 on the press to. This rim also prevents the whole base from being distorted or bent by unequal pressure of the clamps of the press. Should any of these blocks become damaged, the damaged ones can be easily replaced at small expense by others; also, should the base be uneven at places or should the blocks be too thin, paper or other material could be put under the blocks to build up that portion. The construction 70 of the base is such that accurate height to paper, over its entire surface, may readily be secured. The oblique arrangement of the blocks is to guard against many of the tacks for an electrotype falling on the junction of two blocks, but should tacks be driven between blocks as at 7, no obstruction would be met; the only result would be that the tacks would not hold so effectively. 75

The electrotypes are tacked to this wooden 80 surface, in any desired position on the mounting, several being shown in Fig. 1.

The use of the word "blocks" in the following claims does not limit me to the use of square blocks; the blocks may be of any 85 shape that will accomplish the purposes set forth.

I claim as new and desire to secure by Letters Patent:

1. A plate mounting consisting of a rigid 90 tenacious base, a plurality of laminated wooden blocks, and means for independently attaching each of said blocks to said base.

2. A plate mounting consisting of a rigid 95 tenacious base, a plurality of adjacent laminated wooden blocks, and means for independently attaching each of said blocks to said base.

3. A plate mounting consisting of a rigid 100 tenacious base, a plurality of adjacent laminated wooden blocks arranged with their edges oblique to the edges of said base and means for independently attaching each of said blocks to said base, 105

4. A plate mounting consisting of a rigid tenacious base and a plurality of penetrable fibrous blocks substantially covering said base, said blocks being so placed in relation to each other as to allow for their peripheral 110

expansion and contraction and means for independently attaching each of said blocks to said base.

5. A plate mounting consisting of a rigid tenacious base and a plurality of penetrable fibrous blocks substantially covering said base, said blocks being so placed in relation to each other as to allow for their peripheral expansion and contraction and means for independently attaching each of said blocks to said base, whereby the peripheral expansion and contraction of one of the blocks will

not vary the fixed position of any of the blocks.

6. A plate mounting consisting of a rigid tenacious base and a plurality of penetrable fibrous blocks substantially covering said base and means for independently attaching each of said blocks to said base, whereby the peripheral expansion and contraction of one of the blocks will not vary the fixed position of any of the blocks.

ARTHUR K. TAYLOR.
